CAR COUPLING.

No. 338,014.

Patented Mar. 16, 1886.

UNITED STATES PATENT OFFICE.

JULIUS ALFRED ALEXANDER, OF MONTICELLO, ARKANSAS.

CAR-COUPING.

SPECIFICATION forming part of Letters Patent No. 333,014, dated March 16, 1886.

Application filed June 18, 1885. Serial No. 169,035. (No model.)

To all whom it may concern:

Be it known that I, JULIUS ALFRED ALEXANDER, a citizen of the United States, residing at Monticello, in the county of Drew and State of Arkansas, have invented a new and useful Improvement in a Car-Coupling; and I hereby declare the following to be a full and clear description thereof.

This invention relates to a car-coupling the draw-head of which has an internal conically-shaped recess, and in connection with which I use a curved round-pointed connecting-link, as is hereinafter more fully explained.

The invention will be readily understood by reference to the accompanying drawings, of which Figure I is a front end elevation of the end of a car provided with one of my improved couplings. Fig. II is a side elevation of said car with my improved coupling. Fig. III is a plan of the said car and coupling. Fig. IV is an enlarged longitudinal sectional elevation of the draw-head and the mechanism of the improved coupling attached thereto. Fig. V is a transverse sectional elevation of the said draw-head and the mechanism attached thereto. This elevation is taken on the line $x-x$ of Fig. IV. Fig. VI is an enlarged side elevation of the coupling-link.

The draw-head A is attached to the car B in the usual manner with a cushioning-spring, b, interposed between the bearing part of the said draw-head and the fixed frame-work of the car. The sides of the said draw-head are recessed or housed, or otherwise provided with substantial ways a for retaining in its proper relative position a vertically-sliding frame, C, which is arranged to slide up and down in said ways a and to carry with it the coupling-pin D, which passes through and is held in place by the top transverse bar, c, of said sliding frame. The bottom transverse bar, c', of the said sliding frame is engaged by a spring, E, which is arranged to habitually throw the said frame C downward, the said spring E being secured to the bottom side of the draw-head A, and otherwise arranged to readily act upon the frame C to throw or press it downwardly. The draw-head A has an internal conically-shaped recess at a' for the re-

ception of the coupling-link F, and above this conically-shaped recess a' there is also formed another longitudinal recess for the introduction of a spring-buffer, A'. A spring, a³, behind this buffer habitually throws it out, as shown in dotted lines in Fig. IV, but allows it to slide back into the position shown by full lines in the said figure, and in this rearward position the hole or aperture a⁵ in the shanks a⁶ of the said buffer permits the coupling-pin D to drop down into its position for holding the link F in the said draw-head A in the usual manner. When the aforesaid sliding frame C is raised up, and the buffer A' is thrown forward as its spring a³ is normally set to place it, the shank a⁶ of the said buffer is interposed below the pin-hole a⁵ and prevents the said pin from dropping down in the way of the coupling-link F when the latter is inserted in its aperture a' of the draw-head, but as soon as another car comes up its buffer strikes the projecting buffer and pushes it back on its spring a³, and thereby places the aperture a⁵ under the pin D and allows it to drop down into and hold the coupling-link F surely attached to the draw-head A in the usual manner. The sliding frame C is coupled by a link, C', with a sliding bar, H, which is fitted to slide vertically in ways or lugs h, secured to the end of the car B, and the said sliding bar is operated or moved up by either of the levers H' H² H³, which are pivoted or fulcrumed to the car, and operated, respectively, from the sides or top of the car, so that a car can be uncoupled or set to couple or not to couple from the top or from either side of it, as the case may be. Slides h' h² are fitted to the sides of the car so they may be shoved out over and lock either of the levers H' or H², as desired, and a locking-plate, h³, is pivoted to the top of the car or to a lug secured thereto, so that the said locking-plate may be turned out over the lever H³, as shown by dotted lines in Fig. III, so as to lock or hold it down, and consequently the frame C and pin D up when it is so required.

The coupling-link F has its ends respectively curved up or down, as the case may be, as shown at f' and f² in Fig. VI. This per-

mits the end of the link to enter a draw-head readily, either on the same level as the one to which it is attached or one higher or lower than it. When these couplings are in use, 5 and a car is to be uncoupled and set to couple or not to couple, as the case may be, the link F, constructed in this manner and having its ends curved toward the same side, as shown in Fig. 6, is capable of being used with either 10 of its sides upward, and consequently when inserted with its concave side down acts lever- wise in the mortise or draw-head aperture for it, with its outward end depressed below a level line, and thereby adapted to couple with 15 a car at a lower level, and when turned with its concave side upward it in a like manner has its outward end raised up above a level line and adapted to couple with a car at a higher level. The train-men need only operate 20 one of the levers H', H², or H³ to effect the desired result, and as soon as the said levers or either of them is operated so as to raise the frame C up in its ways a far enough to raise 25 the lower end of the pin D above the shank of the buffer A', the spring of the said buffer will throw it forward under the point of said pin and hold it up until the next car comes up to couple on, and then as soon as its buffer strikes the buffer A' it will push it back from 30 under the end of the pin D, and automatically allow it to drop down into the coupling-link F, and so automatically couple two cars together. The pin D is attached to the cross- 35 bar c of the frame C, so that the pin and frame move up and down together.

I am aware that draw-heads for railway-cars have heretofore been constructed with conical recesses in their front ends for the reception of the link; but the curved link I have shown and described, in combination with a draw- 40 head of such a formation, is an important feature in this my invention.

Having thus described my invention, what I claim as new, and desire to secure by Letters Patent, is—

1. The spring-actuated frame C, pin D, sliding buffer A', and vertical spring a³, combined and adapted to operate substantially as shown and described.

2. The combination of a draw-head having 50 a conically-shaped link-recess, a', pin D, its carrying-frame C, spring E, acting habitually to press the frame in a downward direction, the slotted sliding buffer A', and the vertical spring a³, substantially as shown and described.

3. The sliding frame C, the pin D, link C', sliding bar H, and operating-levers H' H² H³, combined and operated as described.

4. The locking slides h' h² h³, fitted to the car B, and operating to lock the levers H' H² 60 H³ in place when required, substantially as shown and described.

In witness whereof I have hereunto set my hand this 22d day of May, 1885.

JULIUS ALFRED ALEXANDER.

In presence of—

D. T. HYATT,
JNO. G. MCKENNEY.
